J. HERBST

SHEET METAL HEATING STOVE

Filed Aug. 16, 1922

INVENTOR

JACOB HERBST

Carlo P. Griffin,
ATTORNEY

UNITED STATES PATENT OFFICE.

JACOB HERBST, OF SAN FRANCISCO, CALIFORNIA.

SHEET-METAL HEATING STOVE.

Application filed August 16, 1922. Serial No. 532,187.

To all whom it may concern:

Be it known that I, JACOB HERBST, a citizen of the United States, residing at San Francisco, in the county of San Francisco, State of California, have invented a new and useful Sheet-Metal Heating Stove, of which the following is a specification in such full and clear terms as will enable those skilled in the art to construct and use the same.

This invention relates to a sheet iron heating stove, and its object is to provide a connection for the bottom of the stove, with the side thereof, which will be more conveniently assembled than the ordinary double seamed joints, and which will not require an additional seaming operation when the bottom is secured to the lower edge of the sheet metal forming the sides of the stove.

Another object of the invention is to provide the legs of the stove with means to more effectually support the stove.

It will be understood by those skilled in the art, that in sheet metal stoves of the character disclosed herein, that if the legs are directly secured to the sides of the stove, without other precautions to make a very substantial job because the sheet metal is so thin, that should it get red hot, the sheet metal will simply bend and allow the stove to settle on the floor.

With the present invention the screws holding the legs to the stove pass through two thicknesses of sheet metal of the stove and the legs have a shoulder upon which the edge of the stove side and bottom rests and the leg has an upwardly extending portion to which the stove material is bolted.

Other objects of the invention will appear as the description proceeds.

An embodiment of the invention is shown in the accompanying drawing in which the same reference numeral is applied to the same portion throughout, but I am aware that there may be modifications thereof.

Fig. 1 is a perspective view of the stove as it appears when complete.

Fig. 2 is a sectional view of a portion of the stove showing the manner of securing

the bottom thereto, and showing two of the legs supporting the stove.

Fig. 3 is an enlarged sectional view showing one leg and a portion of the bottom and side of the stove as it appears when connected to the leg.

The numeral 1 indicates the sheet metal stove which is oval in shape, and which has the smoke pipe opening 2, fuel supply opening cover 3, a draft regulator 4. The stove is provided with 4 legs, 5 to 8 inclusive.

The bottom of the stove is shown at 9, and it is bent downwardly to produce a flange 10, said flange having a beaded edge 11 which tightly fits over the lower edge of the stove, as indicated at 12, the beaded edge 11 is simply forced over the lower edge of the stove, and then the stove sides are secured to the downwardly flanged portion of the bottom by spot welding at a plurality of points as indicated at 13.

The stove legs each have a notch or shoulder at 14 to receive the beaded edge 11 of the bottom flange and they have upwardly projecting ears 15 through each of which two bolts 16 and 17 pass.

It will be noted that the bolts 16 and 17 pass through the lower edge of the side of the stove and also through the down-turned flange 10 of the bottom, thereby giving the connection of the bottom to the sides additional strength as well as making the connection of the stove with the legs stronger than it would be if the supporting bolt for each leg passed only through the side of the stove.

What I claim is as follows:—

A sheet metal stove comprising a side, a top, and a bottom having a downwardly extending flange outwardly turned at its lower edge to receive the lower edge of the side, supporting legs each leg having a curved groove to fit and form a seat for the lower edges of the stove side and bottom flange and a bolt to secure each leg to the stove.

In testimony whereof I have hereunto set my hand this 8th day of August, A. D. 1922.

JACOB HERBST,
